UNITED STATES PATENT OFFICE.

EMERSON C. MCFADDEN, OF SHORT HILLS, NEW JERSEY.

DRAFTING INSTRUMENT.

Application filed April 28, 1924. Serial No. 709,488.

My invention relates to a drafting instrument adapted to provide in a single device a simple and easy means of making sketches and drawings, and of particular advantage 5 in the making of perspective and isometrical perspective views and sketches of various sorts involving or including oblique lines.

The device is preferably made of transparent material, such as celluloid, and the 10 preferred form is illustrated in the accompanying drawing.

Referring to said drawing, the device as a whole is designated by reference character 10 and may consist of a piece of sheet celluloid or equivalent preferably transparent material.

The device is preferably in the form of a five sided figure, making up substantially a rectangle so far as three of the sides are 20 concerned, and having the fourth boundary divided into two parts with a reentrant angle between them. In this way, the base or side opposite the fourth boundary can be provided with an ordinary scale, as in 25 inches, for laying out horizontal, vertical, etc., distances, and the upper sides can be arranged at such angles to one another and to the horizontal and with such scales laid out thereon as to keep length, breadth or 30 thickness, and height in suitable proportions to give a good perspective view.

The five sides or edge portions referred to are indicated by reference characters 12, 14, 16, 18 and 20. The base 12 is provided 35 with a scale 12^a in standard units, as inches, and is used for measuring or laying out any parts which are to appear in the drawing of actual length, as, for example, vertical distances. The ends 14 and 20 may be 40 provided with similar scales if desired, but these scales are not essential and may be dispensed with, particularly where the base side 12 is relatively long, and may be made use of to measure distances considerably 45 longer than could be laid out or measured with the sides 14 and 20.

Side 14 is at a right angle to base 12, so that when aligned with the edge of the paper it may be used to keep the instrument 50 in position with the base line 12 perpendicular to the edge of the paper. Side 20 is also preferably perpendicular to base line 12, so that it may be used in the same way as side 14, and may also be used in the 55 position shown for drawing vertical lines toward the right hand side of the view, or, in

reversed position, for drawing vertical lines toward the left hand side of the view.

Sides 16 and 18 are formed in such a way as to suitably represent width and length respectively in a perspective or isometric view. In the form shown, side 16 for representing width is inclined downwardly from the vertical edge 14 at an angle of about 25 degrees to the base 12, and side 18 for representing length is inclined upward towards the edge 20 at an angle of about 7.5 degrees to the base 12, and the reentrant angle 22 between sides 16 and 18 is about 147.5 degrees, but there may be more or less variation in these angles, which are chosen to give a good perspective representation.

As length and width are foreshortened in perspective views, the scales 16^a and 18^a are suitably foreshortened. A suitable proportion for scale 16^a is on the basis of $\frac{1}{8}$ inch 75 per inch of actual width and for 18^a, $\frac{7}{8}$ inch per inch of actual length, but here too there may be more or less variation, as will be understood.

Provision is also made for guides for making elliptical outlines slanting to right or left or horizontal for drawing lines to represent circles or circular openings or surfaces, and in the form shown, the celluloid material is shown as being provided with suitable cutouts for this purpose.

For this purpose I have shown adjacent to side 14 the small left slanting elliptical cutout 24 and cutout ellipse parts 24^a and 24^b surrounding 24 and adapted for making larger ellipses or parts thereto. Adjacent to side 20 I have shown the provision for making right hand slanting ellipses comprising a relatively small central elliptical cutout 26 and surrounding larger ellipse guide cutouts 26^a and 26^b respectively. In substantially the central portion of the device I have arranged a guide for making non-slanting ellipses comprising the central elliptical cutout 28 and surrounding partial elliptical cutouts 28^a for somewhat larger ellipses.

In laying out angular lines in the oblique portions of views representative of length and breadth, it is desirable to have protractors arranged with their bases on the necessary slant, and I, therefore, provide the two protractors 30 and 32 adjacent to the sides 16 and 18 and having their bases 34 and 36 parallel to sides 16 and 18 respectively.

It will be seen that the instrument serves as a valuable guide for laying out sketches and drawings and enables very satisfactory results to be obtained by users having little or no knowledge of drafting. In making use of the instrument for making isometrical perspective views, the lines representative of width and length are drawn along sides 16 and 18 with side 12 perpendicular to the side edge of the paper, and scales 16^a and 18^a are used to lay off length and width dimensions, and the vertical lines are drawn to scale using full size scale 12^b for this purpose. Where a circle or part thereof is required to be made in the width or length of a view, the elliptical guides of the proper slant are used, correct slant being obtained by keeping the appropriate edge of the instrument at a right angle to the edge of the paper, as will be readily understood. In this way representative sketches and drawings can be readily produced with a minimum expenditure of time and trouble, and the proper angles and lengths are determined in a very simple way and substantially automatically by merely shifting the instrument about in proper relation to the edge of the paper.

I claim:

30 1. A drafting instrument for making oblique views, comprising a five sided plate of celluloid or like transparent material, the longer base side thereof being divided into standard scale units, the sides adjacent to 35 the base extending at right angles to the base, and the boundary opposite the base comprising a part extending inwardly at about 25 degrees to the base and a meeting part intersecting the first part at a reentrant angle of about 147.5 degrees, said 40 parts being provided with scales foreshortened with respect to the standard unit and serving when the base line is horizontal for drawing of lines representative of 45 width and length of objects represented in oblique views.

2. A drafting instrument comprising a plate having a substantially straight base edge serving to determine the position of 50 the instrument when the same is in use and serving as a guide in making certain of the lines of a perspective view, and edge portions at the opposite side of said plate serving as guides for making the other angularly arranged length and breadth lines respectively of said perspective view; said 55 opposite edge portions being arranged at different predetermined angles to said base edge and at an angle to each other; and the 60 angles thereof being coordinated to locate said length and breadth lines in the proper angular relation to each other, and produce a good perspective view.

3. A drafting instrument comprising a 65 plate having a substantially straight base

edge provided with calibrations and serving to determine the position of the instrument when the same is in use and serving as a guide in making certain of the lines of a perspective view, and edge portions at the opposite side of said plate serving as guides for making the other angularly arranged length and breadth lines respectively of said perspective view; said opposite edge portions being arranged at different predetermined angles to said base edge and at an angle to each other; and the angles thereof being coordinated to locate said length and breadth lines in the proper angular relation to each other, and produce a good perspective view, and calibrations of said opposite edge portions foreshortened relative to the calibrations on said straight edge and varying in size in accordance with the angularity of said opposite edge portions relative to said straight edge.

4. A drafting instrument comprising a plate having a substantially straight base edge serving to determine the position of the instrument when the same is in use and serving as a guide in making certain of the lines of a perspective view, and edge portions at the opposite side of said plate serving as guides for making the other angularly arranged length and breadth lines respectively of said perspective view; said opposite edge portions being arranged at different predetermined angles to said base edge and at an angle to each other; and the angles thereof being coordinated to locate said length and breadth lines in the proper angular relation to each other, and produce a good perspective view, and protractors on said plate associated with said opposite edge portions, and each protractor having the base thereof arranged parallel with its respective opposite edge portion.

5. A drafting instrument comprising a plate having a substantially straight base edge serving to determine the position of the instrument when the same is in use and serving as a guide in making certain of the lines of a perspective view, and edge portions at the opposite side of said plate serving as guides for making the other angularly arranged length and breadth lines respectively of said perspective view; said opposite edge portions being arranged at different predetermined angles to said base edge and at an angle to each other; and the angles thereof being coordinated to locate said length and breadth lines in the proper angular relation to each other, and produce a good perspective view, and cut-out portions in said plate associated with said opposite edge portions for drawing ellipses corresponding to the inclinations of said opposite edge portions.

6. A drafting instrument comprising a five sided plate having a straight lower edge

calibrated in standard units, end edges at right angles to said lower edge and two edge portions of unequal length at the opposite side of said plate serving as guides for making the angularly arranged length and breadth lines of a perspective view, and directed inwardly towards said lower edge at different predetermined angles relative thereto and forming a reentrant angle therebetween; and the angles thereof being coordinated to locate said length and breadth lines in the proper angular relation to each other and produce a good perspective view, and calibrations on said opposite edge portions foreshortened relative to said standard calibrations in accordance with the inclinations of said opposite edge portions relative to said straight edge.

10 In testimony whereof, I have signed my name hereto.

EMERSON C. McFADDEN.
